UNITED STATES PATENT OFFICE.

PHILIP J. HARRAH, OF BLOOMFIELD, INDIANA.

MACHINE FOR FORMING METALLIC FENCE-POSTS.

No. 856,864.

Specification of Letters Patent.

Patented June 11, 1907.

Application filed November 14, 1906. Serial No. 343,395.

To all whom it may concern:

Be it known that I, PHILIP J. HARRAH, of Bloomfield, in the county of Greene and State of Indiana, have invented certain new and useful Improvements in Machines for Forming Metallic Fence-Posts; and I do hereby declare the following to be a full, clear and exact description of the invention, such as will enable others skilled in the art to 10 which it appertains to make and use the same.

The object of this invention is to provide a simple and highly efficient machine for forming sheet metal fence posts, being specially 15 designed for forming that class of posts having wire-engaging tongues in their front faces.

The invention will be hereinafter fully set forth and particularly pointed out in the 20 claims.

In the accompanying drawings, Figure 1 is a side elevation, portions of some of the gear wheels being broken away. Fig. 2 is a plan view, with parts omitted. Fig. 3 is a vertical sectional view on line 3--3, Fig. 1. Fig. 4 is a detail. Fig. 5 is a diagrammatic view, partly in section. Fig. 6 is a fragmentary sectional view of one of the female crimping dies. Fig. 7 is a fragmentary edge view of 30 one of the female punching dies.

Referring to the drawings, 1 designates the main frame wherein are mounted three sets of co-operating rotary dies; the first set being composed of an upper male die 2, and 35 a lower female die 3; the second set of an upper male die 4 and a lower female die 5, while the third set is composed of two corresponding upper and lower female dies 6 and 7. The male dies 2 and 4 are formed on 40 their peripheries with tapered ribs, while the female dies 3 and 5 in their peripheries have correspondingly tapered grooves. The rib and groove of the dies of the second set are of smaller cross sectional area than the rib and 45 groove of the dies of the first set, so that a blank first crimped or corrugated by the latter will have a deeper crimp or corrugation formed therein by the second set of dies. The co-operating grooves of the third set of 50 dies accommodate the full width of the post-blank and compress the sides so that the longitudinal edges will be forced together. The narrow ends of the ribs of the two male dies 2 and 4 and the corresponding narrow ends 55 of the grooves of the female dies 3 and 5 are so positioned relatively that the narrow co-

acting portions of the second set of dies will not begin to co-operate until the first set of dies has crimped or corrugated a blank to the extent represented by the distance between lines intersecting the axial centers of the dies of each set, the blank being fed by the first set to the second, and by the latter to the third or completing dies.

The shafts 8 of the lower dies are mounted 65 in bearings 9 on frame 1, and each is equipped at one end with a gear wheel 10. The shafts 12 of the upper dies are mounted in vertically movable bearings 13 constantly under the tension of springs 14, and each of said 70 shafts is equipped with a gear wheel 15 which meshes with its corresponding respective gear wheel 10 so that the co-acting dies will move in unison. Between the gear wheels 10 of the first and second sets of dies 75 is an intermediate gear pinion 16, meshing with both of such wheels, while a similar pinion 17 meshes with the respective wheels 10 of the second and third sets of dies, so that power applied to one set of dies will be communicated to the remaining sets, all of which must move in unison. The shaft 12 of the first set of dies carries at that end opposite to the side whereon the described train of 80 gearing is located, a gear wheel 18 which 85 meshes with a gear pinion 19, which in turn is driven by a gear wheel 20 on an operating shaft 21 carrying a belt pulley 22.

23 designates a rotary die carrying on its periphery tongues or lugs 24 and fast on 90 shaft 21, which latter is mounted in vertically-movable bearings 25, which are constantly under the tension of heavy coil springs 26. This die 23 co-operates with a female die 27 fast on a shaft 28 beneath shaft 21. 95 The female die has in its periphery a series of circular plates 29 formed with central cut-outs 30 to receive and accommodate tongues struck up from the face of a blank, such tongues being employed in practice as wire 100 fasteners. The grooves of the female dies 3, 5 and 7 are provided at their transverse centers with narrow channels 30^a to prevent the tongues being impaired by the passage 105 of the blank through the forming dies.

To avoid forming tongues on the widened or base portion of each blank, I employ two corresponding levers 31, carrying at their rear ends rollers 32 which are engaged by cams 33 on the hubs of the gear wheels of 110 shaft 12 of the male die 2. These levers at their other ends engage the undersides of

bearings 25 of shaft 21 so that when the levers are depressed by cams 33 said bearings will be moved upwardly as against the tension of springs 26 and thereby the male die 23 will be held out of co-operative relation to the female die 27.

In practice a tapered blank of sheet metal is inserted between the peripheries of the male and female cut-out or tongue-forming dies, the former being actuated by the revolution of the driven shaft 21, which drives the shaft of the female die through the intermeshing gears 31 and 32^a. As the blank is thus fed forward it is taken up by the first set of dies 15 2, 3, and crimped or corrugated longitudinally, and by them fed to the second set of dies for still deeper crimping or corrugation, and thence to the third set of dies wherein the blank is subjected to greater compression and its longitudinal edges are brought together. As the wide end of the blank passes between the tongue-forming dies, the male member thereof is elevated just sufficiently to prevent tongues from being formed 25 therein.

Posts that are intended for employment in connection with gates, or at fence corners, are usually made stouter, and the wires are usually secured thereto by wrapping or 30 otherwise, and hence are not equipped with retaining tongues. I have shown the several sets of male and female dies duplicated on their respective shafts, as at 34, 35 and 36, save that the female dies are not formed 35 with the central chambers 30^a. The dies of these sets further differ from those before described only in that their co-operative portions are of greater cross sectional area. In lieu of the tongue-forming dies I provide 40 feed rolls 37 and 38 mounted similarly to the tongue-forming dies.

I claim as my invention:

1. A fence-post machine comprising co-operating rotary dies constructed to form 45 cut-outs in a portion of the face of a fence-post blank, co-operating rotary dies for crimping or corrugating such post-blank longitudinally after the first mentioned dies have acted thereon, and means for throwing 50 said first mentioned rotary dies out of co-operative relation while a portion of the blank is passing between them.

2. A fence-post machine comprising co-operating rotary dies constructed to form

cut-outs in the face of a fence-post blank, 55 co-operating rotary dies for crimping or corrugating such post-blank longitudinally after the first mentioned dies have acted thereon, and means actuated by the operation of the crimping or corrugating dies for throwing 60 said first mentioned rotary dies out of co-operative relation while a portion of the blank is passing between them.

3. A fence-post machine comprising two co-operating dies constructed to form cut-outs in the face of a fence-post blank, one 65 of said dies being mounted in movable bearings, co-operating rotary dies for crimping or corrugating such post blank longitudinally, levers engaging said movable bearings, and 70 means movable with said second mentioned co-operating dies for actuating said levers to move one of said first mentioned dies out of co-operative relation to the other.

4. A fence-post machine comprising co-operating rotary dies constructed to form 75 cut-outs in the face of a fence-post blank, two sets of co-operating rotary dies for crimping or corrugating such post-blank longitudinally after the first mentioned dies have 80 acted thereon, such second mentioned dies having on their peripheries tapered ribs and grooves, the cross-sectional areas of the rib and groove of the dies of one set being greater than the cross-sectional areas of the rib and 85 groove of the dies of the other set, and co-operating rotary dies having on their peripheries corresponding tapered grooves for compressing a fence-post blank previously 90 crimped or corrugated by the second mentioned dies.

5. A fence-post machine comprising a plurality of sets of co-operative rotary dies, one die of each set having on its periphery a tapered rib and the other die a correspondingly tapered groove, such latter dies having channels at the transverse centers of their 95 grooves, and a set of co-operative dies constructed to form tongues in the face of a fence post blank.

In testimony whereof, I have signed this specification in the presence of two subscribing witnesses.

PHILIP J. HARRAH.
